CLAIM

The ornamental design for a game rooms enclosure, as shown and described.

DESCRIPTION

FIG. 1 is a front perspective of a game rooms enclosure, showing a typical embodiment of my new design—with phantom lines depicting a ceiling and floor plan typical of its environment;

FIG. 2A and B —combine to show a—front elevation of the design—with heavy, vertical phantom lines depicting connection of the two partial views as match lines;

FIG. 3 is a side elevation of the design;

FIG. 4 is a —floor section—view of the design—with phantom lines depicting a typical back wall configuration and typical furnishings including pool tables, game tables and various electronic, video and arcade games;

FIG. 5 is a wall section view of the design—with phantom lines depicting a typical ceiling and floor plan and a typical support and insulation structure; and,

FIG. 6 is a ceiling—section—view of the design—with phantom lines depicting a typical ceiling tile and back wall configuration.
